UNITED STATES PATENT OFFICE.

CHARLES A. NELSON, OF UTICA, NEW YORK, ASSIGNOR TO SAVAGE ARMS COMPANY,
OF UTICA, NEW YORK, A CORPORATION OF NEW YORK.

FIREARM.

1,082,969.

Specification of Letters Patent.

Patented Dec. 30, 1913.

Application filed October 15, 1912. Serial No. 725,948.

To all whom it may concern:

Be it known that I, CHARLES A. NELSON, a citizen of the United States, residing at Utica, in the county of Oneida and State of New York, have invented certain new and useful Improvements in Firearms, of which the following is a specification.

This invention has for one of its objects to provide a simple and reliable safety locking means for firearms, this object having been carried out in the specific form of the invention herein shown and described with reference to the firing mechanism, the sear therefor and the sear-tripping or releasing mechanism of an arm of the kind illustrated, for instance, in the patent to Searle, No. 936369, wherein is employed a device for locking the breech-bolt and the firing mechanism, which device I utilize as a detent in obstructing the firing movement of the firing mechanism, the releasing movement of the sear and the sear-actuating movement of the sear-tripping mechanism.

Another object of the invention is to provide a simple and reliable means for detecting the presence or absence of a cartridge in the breech of the arm.

Still another object of the invention is to improve an arm of the kind illustrated in the said Searle patent in respect to the disassembling thereof.

In the accompanying drawings, Figure 1 is a view of the improved arm mainly in longitudinal vertical section; Fig. 2 is a rear elevation, partly in vertical section through the detent, all parts of the breech mechanism being removed excepting the firing-lever; Fig. 3 is a plan view of the improved locking device; Fig. 4 is a plan view of the forward portion of the arm, with the breech partly broken away to show the improved cartridge detector; Fig. 5 is a side elevation of the breech end of the barrel with said detector in position; Figs. 6 and 7 are side and rear end views of the detector; Fig. 8 is a side elevation of the forward portion of the arm partly broken away to illustrate that part of the present invention relating to the disassembling of the gun; and, Fig. 9 is a vertical sectional view on the line $\alpha-\alpha$ of Fig. 8.

The frame a having the grip b ; the barrel c interlocked with the frame at its enlarged rear portion d ; the breech-bolt e having the removable plug f forming there-

with a breech structure which slides rearwardly on the frame under actuation of the explosion-pressure and is returned by the spring g ; the firing mechanism arranged in the plug f and including the cocking-lever h , a firing pin (not shown) connected therewith and a sear i for locking the firing-pin and lever h in cocked position; the sear-releasing or tripping means including the trigger j arranged to slide back and forth in the frame and the sear-trip k pivoted at its forward end in the trigger and having means l coating with a shoulder m on the frame to lock the sear-trip down out of the path of the sear so as to prevent double firing when, after firing, the sear is carried forward with the breech structure; the locking device or detent consisting of a spindle n journaled in the frame and having a handle o and being adapted, when turned 90° from the position shown in Fig. 1, both to leave the breech mechanism free to move longitudinally and the cocking-lever h free to move against the firing-pin (because at that time a lug p of the cocking-lever coincides with a cross-cut slot q of the spindle n) and being further adapted, when turned into the position shown in Fig. 1, to be received by one or the other of the notches r in the breech bolt, to lock the breech mechanism against longitudinal movement and to oppose firing movement of the cocking-lever (because its slot q is not in registry with the lug p which then impinges against the spindle), and the cartridge magazine s entered into the grip from below, are or may be all substantially the same as in the said patent to Searle excepting as will be herein-after indicated.

Safety locking means.—On a pin t fixed in the lower rear portion of the grip is fulcrumed a lever forming the improved locking device. This lever u is suitably shaped from a piece of sheet metal and includes the part-cylindrical or channeled elongated body part v having two lugs w projecting from its opposite walls at one end thereof and also having arms projecting from its other end and formed as follows: From the wall or side of said body part toward the observer in Fig. 3 project three arms x , y and z ; from the other wall or side projects the arm 2 . The arms x , y and z are arranged in substantially the same plane, and arm 2 is arranged in a plane parallel there-

with, being sufficiently spaced therefrom to freely admit the magazine *s*. The lugs *w*, having suitable holes for the purpose, afford means by which to fulcrum the lever *u* on the pin *t*, which lever is so formed that when properly assembled with the grip of the arm with its convex side facing rearwardly, its body part *v* is exposed by a rearward opening *3* in the grip. Normally the lever 10 is pressed rearwardly, abutting against the frame at the upper end of said opening *3*, by a spring *3'* which is coiled about the pin *t* and has one end bearing against the inside of the body part *v* of the lever and its other 15 end engaged in a notch *4* in the grip. In this position of the lever its arm *x* abuts a lug *5* projecting rearwardly from the trigger *j* while its arm *y* abuts the depending portion of the sear *i* whose fulcrum is at 20 about the point *6*; the cocking-lever is shown in the cocked position in Fig. 1, and in that position the arm abuts the heel *7* at the forward end of the cocking-lever. Thus, with the lever *u* locked in the position shown 25 in Fig. 1, it opposes such movement of the trigger, the sear and the cocking-lever as would accomplish firing; with the lever *u* free to move, upon the gun being held by its grip, the hand of the operator, in the effort 30 to draw back the trigger, will move the lever *u* on its fulcrum so as to cause the same to clear the parts *j*, *i* and *h*, allowing them to move to effect firing, the grip-forming elements being so constructed and arranged as 35 to lend themselves naturally to the quick and effective discharge of the gun by gripping and operating it in the usual way.

Locking of the lever *u* in the position shown in Fig. 1 is accomplished by the co- 40 action of spindle *n* of the detent and arm *z* when the detent is in the position wherein it is shown in Fig. 1, at which time said arm bears against the spindle, as shown; when the spindle is turned so as to bring a recess 45 *8* therein into registry with arm *z* the lever *u* is free to move. The extremity of arm *z* is concave to fit the cylindrical surface of the spindle so as to obtain a sufficient purchase upon the arm when the latter is in the 50 locking position to prevent the forward movement of the lever. It will thus be apparent that neither by carelessness in handling nor as the effect of blows or jars, can any of the parts *j*, *i* or *h* assume movement 55 which will result in firing the gun.

Cartridge detecting means.—The enlarged part *d* of the barrel has an exterior circumferential groove *9* formed at its forward end, and extending from said groove to an 60 opening *10* entering to the bore of the barrel at the rear thereof an exterior groove *11*. The detector consists of an elastic metallic piece formed of sheet metal and including a split strap *12* and a finger *13* projecting 65 from one side of said strap and having its

free end rebent inwardly to form a toe *14*. The detector is fitted to the barrel so that the parts *12* and *13* lie in the grooves *9* and *11*, the toe *14* projecting through the opening *10* into the space occupied by the cartridge *A* in the breech of the barrel. In the normal position of the parts the finger *13* is opposite the ejection opening *15* of the breech bolt. If a cartridge is in place in the breech its presence may be detected by the 70 foresfinger of the operator's hand, which will at that time find the detector *13* held more or less outwardly in the opening *15* by the cartridge; absence of a cartridge in the breech will appear if the operator's forefinger finds the finger *13* depressed into its groove *11*. It will be noted that the free 75 end of the detector lies short of the rear end of the barrel, so that it does not interfere with the ejection of the cartridge. 80

Sear-trip.—It has been found that in disassembling a gun of the Searle type (involving removing the plug *f* and then sliding the breech-bolt forwardly to clear it of the frame) the sear-trip *k* occasionally rises 85 high enough to engage the forward side of the adjoining projection *16* forming one of a pair of projections which coact with projections on the plug to hold the latter in place, so that the actuator blocks the disassembling movement of the breech-bolt; this undue rising of the sear-trip, which is supposed to be prevented by the overhanging barrel, occurs through lost motion due mainly to wear of the parts. I therefore 90 cut away the lower forward corner of the said projection *16* preferably so as to form a rearward incline or cam face *17* whereby, when the breech bolt is moved forward in disassembling, the sear-trip will be wiped 95 down instead of opposing possible obstruction to the removal of the breech-bolt. 100

Having thus fully described my invention, what I claim as new and desire to secure by Letters Patent is:—

1. In combination with the frame, mechanism to be controlled arranged therein, a manually moved lever controlling said mechanism and fulcrumed in the frame on a horizontal axis, and a locking device rotatable in the frame also on a horizontal axis and normally opposing movement of the lever, said device having a cut-away portion at one side of its axis affording clearance between said device and the lever when 115 the device is turned, substantially as described.

2. In combination with the barrel of a gun, a cartridge detector having a strap portion embracing the barrel and an outwardly yielding spring finger extending from the strap portion longitudinally of the barrel and normally projecting into the space occupied by a cartridge entered into the barrel, said finger and strap portions of the de- 125

tector being recessed into the barrel, substantially as described.

3. In combination, with the barrel of a gun having an external circumferential groove and an external longitudinal groove leading rearwardly from the first groove, a cartridge detector having a strap fitted into the first groove and an outwardly yielding spring finger extending rearwardly from the strap and fitted into the second groove and normally projecting into the space occupied by a cartridge entered into the barrel, substantially as described.

4. In a gun, the combination of the frame, a breech mechanism arranged thereon and including a forwardly removable bolt slidably arranged on the frame and a breech-plug, the breech-bolt having an internal shoulder interlocking the breech-plug with

the breech-bolt and extending downwardly to the frame, firing means carried by the breech mechanism, and means for releasing the firing means including a normally elevated depressible sear-trip having thrust-movement in the frame substantially parallel with the breech bolt and projecting toward said shoulder, said shoulder having its forward lower portion inclined rearwardly whereby to depress the sear-trip on removing movement of the breech-bolt, substantially as described.

In testimony whereof I affix my signature in presence of two witnesses.

CHARLES A. NELSON.
